UNITED STATES PATENT OFFICE.

ROBERT S. JOHNSON, OF COLEMAN, TEXAS.

TYING ATTACHMENT FOR BALING-PRESSES.

SPECIFICATION forming part of Letters Patent No. 761,305, dated May 31, 1904.

Application filed June 30, 1903. Serial No. 163,790. (No model.)

To all whom it may concern:

Be it known that I, ROBERT S. JOHNSON, a citizen of the United States, residing at Coleman, in the county of Coleman and State of 5 Texas, have invented a new and useful Tying Attachment for Baling-Presses, of which the following is a specification.

This invention relates to improvements in devices of that class for tying, knotting, or 10 otherwise securing the ends of wire to hold bales of compressed material in proper shape.

One object of the invention is to provide a device which may be made and sold as an attachment and readily applied to baling-presses 15 in ordinary use without the necessity of employing specially-skilled labor.

A further object of the invention is to provide a device of simple and economical construction in which a pair or a plurality of 20 pairs of jaws are simultaneously forced through the compression-chamber, the jaws constituting each pair moving, respectively, in opposite directions and carrying a binding-wire to an intermediate point in the compression-chamber, the wire being afterward twisted together by mechanism actuated after the 25 jaws have reached proper position.

A still further object of the invention is to provide a device of this character in which 30 the wire-carrying jaws will at all times be threaded so long as the coil or reel of wire may last, rendering it unnecessary to employ the auxiliary threading mechanism usually used to introduce the wire to the jaws or carriers after operation.

A still further object of the invention is to provide a mechanism of this character which may be conveniently operated by a single workman, rendering it unnecessary to employ 35 any auxiliary power for the purpose.

A still further object of the invention is to provide a novel form of cutting mechanism for severing the wire between two bales, a single twist serving to hold the wire together 40 at the adjacent ends of successive bales.

Other objects of the invention are to provide an improved twisting mechanism and to secure uniformity of the twisting operations by preventing returning movement of the 45 twisting devices until they have been moved to a predetermined extent.

With these and other objects in view, as will hereinafter more fully appear, the invention consists in the novel construction and arrangement of parts hereinafter described, 55 illustrated in the accompanying drawings, and particularly pointed out in the appended claims, it being understood that various changes in the form, proportions, size, and minor details of the structure may be made 60 without departing from the spirit or sacrificing any of the advantages of the invention.

In the accompanying drawings, Figure 1 is a transverse sectional elevation of a portion of a baling-press provided with a tying attachment constructed in accordance with the invention. Fig. 2 is a plan view illustrating the arrangement of the operating devices. Fig. 3 is a sectional elevation of a pair of wire carrying and twisting jaws, taken transversely of 70 the baling-chamber. Figs. 4 and 5 are sectional views, on an enlarged scale, showing the operation of a pair of jaws. Fig. 6 is a detail perspective view of one of the jaws. Fig. 7 is a side elevation of the cutting-knife, showing the knife-carrying jaw in section. Fig. 8 is a diagram showing the arrangement of the tie-wires as they would pass around successive bales without cutting the wires. Fig. 9 is a side elevation of a portion of the top of 80 the press-box and the actuating mechanism.

Similar numerals of reference are employed to indicate corresponding parts throughout the several figures of the drawings.

To the opposite sides of the compression-box are secured vertically-disposed bars 1 and 2, these being slightly spaced from each other and provided with alining openings, forming guides for the slidable wire-carrying jaws. In the present instance two of the jaws are arranged at each side of the compression-chamber for the formation of two wire bales, although any desired number of jaws may be employed in accordance with the size of the bale to be made.

To each side of the compression-chamber is bolted a bracket 3, projecting outward for some distance from the side of the box and bifurcated to receive a forked arm 4, one end of which is pivotally connected by links 5 to 100 a pedal-lever 6, arranged at the top of the compression-box, and within convenient reach

of the foot of a workman standing on said box. This system of levers serves to effect the movement of the wire into the compression-chambers, while a spring or springs 7 serve to withdraw the jaws from the chamber when pressure on the pedal-lever is relieved.

At one side of the compression-chamber are arranged one or more horizontally-guided bars 10, the outer ends of which are connected to the forked arm 4, and at the inner end of each of these bars is a wire carrying and twisting jaw 11. The extreme inner end of the bar 10 is bifurcated to form a pair of centrally-spaced arms 12, having openings for the reception of the hubs or reduced end portions 13 of a ratchet-wheel 14, and the extreme end portions of the arms are slit and so arranged as to form flaring forks 15, through which the wire is directed into a groove or recess 16, formed in the ratchet-wheel and its hub members, and when two wires are introduced into this slot the ratchet-wheel is revolved and twists them together, the ratchet-wheel being held from rotative movement in the opposite direction by means of a small spring-pawl 17. Near the outer ends of each of the bars 10 are arranged two oppositely-directed arms 18 and 19, the arm 18 being bent for a short distance into parallel relation with the main body of the bar, while its extreme outer end is directed outwardly at an angle, and from the end portion there projects an angularly-directed finger 20. The arm 18 is provided with a wire-receiving eye 21, through which the wire extends from the supply-coil. The arm 19 is forked and the fork members are arranged at a slight angle to each other, as indicated at 23, in order to permit their ready engagement with the wire leading from the side of the preceding bale. Under normal conditions the mouth of the slot 16 is in direct alinement with the recesses formed at the ends of the bifurcated portion of the bar 10, and the wire is led from the preceding bale between the forks of arm 19 and thence through the slot of the ratchet-wheel and the eye 21 to the supply coil or reel. At the opposite side of the compression-box the openings in the vertical strips or bars serve to hold the jaw-carrying members 31, each of the same construction and connected to one of the forked arms 4 in order to permit their operation from the pedal-lever. At the extreme inner end of the bar are two oppositely-directed arms 32 and 33, the arm 32 being provided with a wire-receiving eye 34, through which the wire extends from the reel, while the arm 33 is provided with flaring forked members 35, through which the wire is guided from the corresponding side of the preceding bale, and the relative arrangement of the flaring forked members of the opposite jaws is such that the arm 33 will be received slightly within the forks of arm 19, and thus insure the parts being guided to correct position, while the two sets

of forks when brought together form, in effect, a guiding-eye for the two wires. The single wire carried by the arms 32 and 33 extends across between the eye and forked arm in such manner that when the two jaws are moved into engagement with each other the wire will be received within the slotted portion of the ratchet-wheel and when the latter is rotated will be intertwined with the wire already located within the slot. To operate the ratchet-wheel, there is employed a slideable bar 40, one of said bars being carried by each of the sliding bars 31. The lower surface of the inner ends of bar 40 is provided with a rack, the teeth of which intermesh with the teeth of the ratchet-wheel 14 when the bar is moved inward. In order to guide the rack-bar, the bar 31 is provided with a slot 42, with which engages a depending pin 43, carried by the rack-bar, and as a further guiding means the bar 31 is provided with a guide 44 in the form of an inverted U, the side members of which serve to prevent lateral play of the rack-bar. The cross-bar of the guide 44 carries a swinging block 45, the lower end of which is slightly inclined and normally rests in engagement with the upper surface of the rack-bar, so as to positively prevent upward movement of the rack-bar to an extent sufficient to allow its disengagement from the teeth of the ratchet-wheel during the twisting movement, and at the same time this block acts as a friction-pawl to prevent the withdrawal of the rack-bar until the latter has been forced inward to a predetermined extent. This inward movement is governed by a notch 48, which when it arrives under the swinging block allows the block to tilt and move out of locking engagement with the rack-bar, so that the latter is free to return to its initial position. In the outer end of the bar 31 is an opening 50 for the reception of one end of a pivoted catch 51, arranged in a slotted portion of the bar 40, the upper end of said latch being disposed slightly above the upper surface of said bar 40 to permit the engagement therewith of one arm of a bifurcated lever 52, and when so engaged the upper end of the catch is depressed and its lower end moved out of locking engagement with the opening 50, so that inward movement of the rack-bar is allowed after the movement of the jaw 30 has ceased; but during the advancing movement of the jaw 30 the rack-bar will be compelled to travel therewith. As an operating means for the rack-bars, a shaft 53 is arranged in suitable bearings at one side of the compression-box, and the upper end of said shaft has a cranked handle 54 within convenient reach of the operator. The levers 52 are rigidly secured to this shaft and have bifurcated outer ends which embrace headed pins or studs 55, carried by the rack-bars.

In operating the device the jaws are normally clear of the compression-chamber, so

as to permit free operation of the plunger. At the proper time the workman depresses the pedal-lever and through the forked arms 4 and connecting mechanism forces the jaw members inward from opposite sides of the compression-box until the wire carried by the arms 32 and 33 has been inserted in the slot of the ratchet-wheel. Holding the parts in this position the operator then partly turns the crank and moves the levers 52 into such position as to disengage the catches 51 from the openings 50. Continuing the movement of the crank and shaft the rack-bars are forced inward into engagement with the ratchet-teeth and turn the ratchet-wheel until the two wires held therein are firmly twisted together. The pivoted friction-pawl prevents disengagement of the rack-bar from the ratchet-teeth during the twisting operation and further prevents return movement until the twisting operation has been fully accomplished, at which time the slotted portion of the ratchet-wheel will have regained its normal position, the mouth of the slot being open to permit the escape of the twisted wires. This operation is carried on continuously, the wires being introduced from corresponding sides of the formed bales, and as the bales issue from the press-box they may be severed by cutting the twisted portion of the wires at an intermediate point; but it is preferred to accomplish this cutting operation at the end of the twisting movement of the ratchet-wheel. The cutters employed are each in the form of L-shaped cutter-bars 60, mounted on pins at one side of the bifurcated portion of the bar 10, and the lower or substantially horizontal arm of bar 60 is provided with a cutting edge adapted to coact with the end of the ratchet-wheel hub and the wall of the slot therein to effect the cutting of the wire. The rack-bars are each provided with projecting pins 64, which at the completion of the twisting operation are forced into engagement with the vertical arms of the L-shaped bars 60 and move the cutting edges thereof up and past the slot, thereby severing the wires. The beginning of the movement of the cutter-bar will of course occur before the completion of the twisting operation; but the actual cutting operation cannot take place until the slot has approximately reached its initial position. When the cutter is used, the severed portion of the twisted wire at the end of the completed bale will readily escape as the forked portions of the arms 19 and 33 separate, while the remaining portion in advance of a bale to be formed will escape from the slot and will be held between the two eyes of the jaw members, and as the latter are moved outward this twisted portion will remain at about the center of the bale to be formed. When the arms have reached the full outward position, successive movements of the plunger will gradually draw the wire from the coils, the wire

sliding through the eyes and one wire being received within the slot and forked member of the bar 10, while the other is properly guided to position in the jaw carried by member 31. In order to prevent wear, the fork or forks may be provided with antifriction-rollers 70, and said rollers may be curved in order to form guides for the wire.

In carrying out the invention it is to be understood that the actuating mechanism may receive movement from the plunger of the press, and for this purpose the pedal-lever is extended rearwardly and in convenient position to be engaged by a pivoted arm 71, mounted in a suitable bracket at the top of the press-box, the lower end of said arm being adapted to extend within the press-box in position to be engaged by the plunger-head and when so engaged to operate on the pedal-lever and force the wire-carrying arms into proper position in the baling-chamber. This arm 71 is normally held in an inoperative position by a spring 72, which may be released whenever it is desired to permit the plunger-head to effect the desired operation.

The device as described is of such nature as to permit its attachment to baling-presses already in use, although in the construction of new baling-presses these parts may be added without modifications in any material respect.

Having thus described the invention, what is claimed is—

1. The combination with a baling-press, of a pair of wire-carrying jaws movable inward from opposite sides of the press, a twister carried by one jaw, and a twister-operating mechanism carried by the other jaw.
2. The combination with a baling-press, of means for feeding a continuous length of wire from each side of the machine inward to points between successive bales, wire-receiving eyes carried by such feeding means and with which the wire is in constant engagement, and means carried in part by each of such feeding means for intertwisting the wires so introduced.
3. The combination with a baling-press, of a tying attachment adapted for application to the press-box, said attachment comprising wire-carrying jaws adapted to enter the press-box from opposite sides respectively, means for guiding the said jaws, means for operating the jaws, means carried by one jaw for twisting together the wires introduced into the press-box, and an auxiliary means carried by the opposite jaw for actuating said twisting means.
4. In a device of the class specified, the combination with opposing wire-carrying jaws each provided with an eye with which the wire is in constant engagement, means for forcing the jaws toward each other, a slotted revolute member carried by one of the jaws and adapted to receive both wires, and means supported by the opposite jaw for revolving said member to thereby twist the wires together.

5. In a device of the class specified, the combination with a pair of wire-carrying jaws each provided with an eye member with which the wire is in constant engagement, of a forked 5 arm carried by each jaw and serving as a wire-guide, a slotted and revoluble member carried by one of the jaws and adapted to receive the wires from both jaws, and means supported by the opposite jaw for revolving said member and thereby twisting the wires together.
6. In a device of the class specified, the combination with a pair of wire-carrying jaws each having forked arms between which the 15 wires are stretched, a twisting member carried by one of the jaws and adapted to receive the wires of both, and means carried by the opposite jaw for actuating said twisting member.
7. In a device of the class specified, the combination with wire-carrying jaws each including a pair of spaced arms between which the wire is stretched, a revoluble twisting member carried by one of the jaws and provided 25 with a slot for the reception of both wires, and means supported by the opposite jaw for engaging the twisting member and revolving the same, substantially as specified.
8. In a device of the class specified, the combination with a pair of wire-carrying jaws each including forked arms one of the arms of each jaw being provided with a wire-receiving eye in constant engagement with the wire and the other arm of each jaw being forked to form a 35 wire-guide, a twisting member carried by one of the jaws, and means carried by the opposite jaw for actuating said twisting member.
9. In a device of the class specified, a pair of wire-carrying jaws each provided with a pair 40 of arms, one of the arms of each jaw having a wire-receiving eye in constant engagement with the wire and the other arm of each jaw being forked to form a wire-guide, the forked arms interlocking to form an eye for the reception of the two wires, a twisting member carried by one jaw, and means carried by the opposite jaw for actuating said twister.
10. In a device of the class specified, a pair of wire-carrying jaws having interengaging portions and each adapted to receive and guide a wire, a revoluble twisting member carried by one jaw and slotted to receive both wires, and means carried by the opposite jaw for actuating said twister.
11. In a device of the class specified, a pair of carrying-jaws each provided with a wire-receiving eye in constant engagement with the wire and each having a wire-guiding fork, the fork members being adapted to interlock to 55 form in effect an eye for the reception of both wires, a twister-bar carried by one of the jaws and adapted to receive both wires, and means carried by the opposite jaw for actuating said twister.
12. In a device of the class specified, a pair of 60 wire-carrying jaws, means for reciprocating the same toward and from each other, a toothed twisting member carried by one jaw and provided with a wire-receiving slot, and a rack supported by the opposite jaw and adapted to engage said toothed twisting member.
13. In a device of the class specified, a pair of wire-guiding jaws, means for reciprocating said jaws toward and from each other, a toothed twisting member carried by one of the jaws 75 and provided with a wire-receiving slot, means for guiding both wires into the slot, and a slidable rack for engaging the twister and revolving the same.
14. In a device of the class specified, a pair of wire-guiding jaws, means for reciprocating the jaws toward and from each other, a slotted twister having peripherally-disposed teeth and revolubly mounted in one of said jaws, means for guiding both wires into said slot, 80 and a slidable rack-bar for engaging and rotating said twister.
15. In a device of the class specified, a pair of wire-carrying jaws having means for holding the wire, a bifurcated arm having bearing-90 openings, a ratchet-wheel having hubs or extended portions adapted to the bearing-openings, there being a wire-receiving slot extending through the ratchet-wheel hubs, and the bifurcated arms being forked to permit the 95 passage of the wire into said slot, a rack-bar carried by the opposite jaw, and means for actuating said rack-bar.
16. In a device of the class specified, a pair of wire-carrying jaws, a toothed twisting-wheel 100 carried by one of the jaws, and slotted for the reception of the wires, a rack-bar slidably mounted on the opposite jaw, means for guiding the said rack-bar, and a friction-dog engaging with said rack-bar and serving to hold 105 the same in engagement with the teeth of the twister-wheel.
17. In a device of the class specified, a pair of wire-carrying jaws, a toothed twister-wheel carried by one of the jaws and provided with 110 ratchet-teeth a rack-bar slidably mounted on the opposite jaw and provided with a notched portion, and a friction locking-dog engaging with the bar and serving to prevent rearward movement of the same until the dog comes opposite the notch.
18. In a device of the class specified, the combination with a pair of wire-carrying jaws, of a toothed twister-wheel carried by one of the jaws and provided with a wire-receiving slot, 115 a rack carried by the opposite jaw and adapted to engage the teeth of the twister-wheel, means for locking the rack to the jaw member during the upward movement of the latter, and means for disengaging the rack and moving 120 the same to effect the twisting operation.
19. In a device of the class specified, the combination with wire-carrying jaws, of twisting means carried by one of the jaws, a cutter-bar carried by the same jaw, and means carried by 130

the opposite jaw for actuating the twister and the cutter-bar.

20. In a device of the class specified, the combination with a pair of wire-carrying jaws, of 5 a slotted twister-wheel and a cutter-bar carried by one of the jaws, a rack carried by the second jaw and adapted to engage with and operate the twister-wheel, and a lug or pin carried by said rack-bar for moving the cutter-bar to operative position.

21. In a device of the class specified, the combination with a plurality of wire-carrying jaws, wire-twisting devices, supporting-brackets, forked arms carried by the brackets and 15 connected to the jaw members, a pedal-lever connected to the forked levers, a rock-shaft, and means for connecting the rock-shaft to a portion of the twister-actuating mechanism.

22. In a device of the class specified, the combination with a press-box, of pairs of plates or 20 bars secured to the opposite sides of the press-box and provided with guiding-openings, wire-carrying jaws having bar or shank portions adapted to the guiding-openings, a pedal mechanism operatively connected to said jaws, a 25 twister mechanism, and a rock-shaft having operative connection with said twister mechanism.

In testimony that I claim the foregoing as my own I have hereto affixed my signature in 30 the presence of two witnesses.

ROBERT S. JOHNSON.
